UNITED STATES PATENT OFFICE

WILLIAM R. GULICK, OF JERSEY CITY, NEW JERSEY.

PROJECTILE.

1,096,907.

Specification of Letters Patent.

Patented May 19, 1914.

Application filed July 19, 1912. Serial No. 710,357.

To all whom it may concern:

Be it known that I, WILLIAM R. GULICK, a citizen of the United States, residing at 93 Garrison avenue, in Jersey City, county 5 of Hudson, State of New Jersey, have invented certain new and useful Improvements in Projectiles, of which the following is a specification.

The invention relates to projectiles for 10 rifled fire arms or ordnance and one of the primary objects of the invention is to provide means whereby the projectile will submerge and hold its true course upon coming in contact with a liquid such as water instead of ricochetting therefrom.

A further object of the invention is to provide means whereby the normal resistance of the air to the projectile in its flight may be diminished.

20 The various other objects of the invention will be more fully set forth in the following description of one form of projectile embodying the invention which consists in the new and novel features hereinafter set forth 25 and claimed.

Referring to the accompanying drawings:—Figure 1 is a side view of a horizontally positioned projectile. Fig. 2 is a side view at right-angles to that of Fig. 1, and 30 Fig. 3 is a front view of the projectile.

The projectile may be of any desired form and type, for instance, it may be a shot or shell, and may be pointed at the head, rounded, or otherwise.

35 In the particular construction shown in the drawings the projectile A is provided with a head B of reduced diameter provided with a cap C. A plurality of oppositely disposed members D having their peripheries within the circumference of the body portion of the projectile are mounted upon or formed integral with the head. Said members are plain or flat flanges oppositely inclined preferably at a small or low angle 40 with respect to the axis of the projectile so that one edge of each flange will extend forwardly and outwardly, but within the circumference of the body portion. The flanges are preferably arranged in pairs diametrically opposite each other and encircling respectively opposite halves of the reduced portion of the projectile. The flanges are 45 of proper shape and configuration to accurately balance each other while the projectile is in its flight or passage. Suitable

clearance space is provided between the ends of the flanges and the body portion of the projectile in any suitable manner.

The rotary movement of the projectile which is imparted by the rifling of the arm 60 or ordnance causes the flanges to cut through either air or water, thus tending to secure a straight trajectory for the projectile and also tending to increase the velocity of the projectile, particularly through a resisting 65 medium such as water. The flanges are so arranged that at least one of them must engage with the water prior to the instant of contact of the body of the projectile therewith and on account of the rotary movement of the projectile have the effect of preventing ricochetting and cause the projectile 70 to follow its path beneath the surface.

By means of this construction I am enabled to provide a projectile which will enter the water and which will follow its course for a considerable distance while submerged on account of the propelling action of the flanges due to the rotary movement 75 of the projectile. Not only do the 80 flanges cause the projectile to submerge, but they also aid in the flight of the projectile through the air since the rotary movement of the flanges tends to penetrate the air blanket or cap which forms at the point of 85 any swiftly moving body.

Although I have shown the projecting flanges secured directly to a reduced portion of the projectile it is obvious that they may be placed in any desired position provided 90 they oppose and balance each other and provided also that sufficient clearance is provided in the rear of the flanges to permit the passage of a fluid such as air or water with respect thereto.

95 It is obvious also that various other modifications and changes may be made in the construction shown in the drawings provided the means set forth in the following 100 claims be employed.

Having thus described my invention, I claim:—

1. A projectile for rifled fire arms adapted to enter and keep its course through water comprising a body portion and a reduced 105 end portion, flanges extending outward from the reduced portion and within the line of the body portion and mounted on opposite sides of the projectile and operatively inclined thereto for aiding the projectile to 110

dive into water and keep its course therethrough during the rotation of the projectile imparted by the rifling.

2. A projectile for rifled fire arms having
5 a pair of similar flanges projecting laterally from the same adjacent its forward end, said flanges being equally and oppositely inclined and respectively encircling opposite halves of the projectile for aiding the
10 same to pass from a medium of one density into a medium of different density and keep its course therethrough during rotation of the projectile imparted by the rifling.

3. A projectile for rifled fire arms having
15 a reduced portion at one end and a pair of similar flanges projecting laterally from

said reduced portion to a point within the line of the body portion of the projectile, said flanges being equally and oppositely inclined and respectively encircling opposite halves of said reduced portion for aiding the projectile to dive into water and keep its course therethrough during rotation of the projectile imparted by the rifling, said reduced portion extending rearwardly 20 25 of the flanges to free them of the water.

This specification signed and witnessed this 17th day of July, A. D., 1912.

WILLIAM R. GULICK.
